(57) **CLAIM**

The ornamental design for an electronic peripheral device, as shown and described.

DESCRIPTION

FIG. 1 is a top perspective view of the electronic peripheral device.

FIG. 2 is a top perspective view of the electronic peripheral device with a cover removed.

FIG. 3 is a front view of the electronic peripheral device.

FIG. 4 is a rear view of the electronic peripheral device.

FIG. 5 is a top view of the electronic peripheral device.

FIG. 6 is a bottom view of the electronic peripheral device.

FIG. 7 is a side view of the electronic peripheral device; and, FIG. 8 is an opposite side view of the electronic peripheral device.

The broken line showings of the connector in FIG. 2 are for the purpose of illustrating portions of the electronic peripheral device and form no part of the claimed design.
